TELEPHONE SYSTEM

Reginald Griffith Dixon, London, England, assignor to Siemens Brothers & Company Limited, London, England

Application December 24, 1931, Serial No. 583,051
In Great Britain December 24, 1930

14 Claims. (Cl. 179—18)

The present invention relates to automatic telephone systems and is especially suitable for systems employing line finders.

In this invention a switch has its outlets grouped, each group being connected to a different multiple, the multiples being associated with different switching stages, and the switch operates as a backward hunting or forward selecting switch as required, the group of outlets in which the switch performs its hunting or selecting movements being determined by the function of the switch, i. e. whether it is operating in a backward hunting or forward selecting capacity.

Two such switches may be connected to the ends of a link circuit, the link circuit being connected to the switch wipers, and either switch may operate as a backward hunting switch as required, the other then operating as a forward selecting switch.

As regards the outlets of a switching stage these may be divided into groups, one group being accessible to one switch of the pair and the other group to the other switch of the pair.

For co-operating with the outlets of the two switching stages, a switch may be provided with two wiper sets, one set being used when the switch operates as a backward hunting switch, the other set being used when the switch operates as a forward selecting switch.

The determination as to which switch of a linked pair is to operate as a backward hunting switch and which as a forward selecting switch may be made in a control circuit common to a group of linked switches, and the association of a control circuit with a particular link may be effected by a hunting switch. The control circuit preferably comprises the necessary arrangements for stepping the switches, and for the control of the forward selecting switches, is preferably provided with impulse receiving and repeating arrangements.

A pair of linked switches according to the invention may be employed as a line finder and group selector, incoming lines being divided into two groups, one group appearing as outlets in one switch and the other group as outlets in the other switch, outlets to a succeeding switching stage being similarly connected so that the two switches may operate on different groups. The switches are conveniently 200 point switches having two banks of 100 outlets each, and two switching relays only are required.

For the better understanding of the invention reference will now be had to the accompanying drawings which show by way of example an em-

bodiment of the invention. In the drawings Fig. 1 shows a link circuit comprising two switches either of which may act as a call finder, the other acting as a group selector, and Figs. 2a and 2b show a control circuit associable with any one of a number of link circuits for controlling the operation of the switches of a link circuit.

The link circuit shown in Fig. 1 comprises two switches A and B, the former represented by the wipers AF1, AF2, AF3, AS1, AS2, AS3 and magnets AV, AR, and AZ and the latter by the wipers BF1, BF2, BF3, BS1, BS2, BS3 and the magnets BV, BR and BZ. Each switch has included in it a set of level marking contacts ANP, BNP which are engaged by a wiper having movement in a vertical direction only and vertical off normal contacts denoted by the letters *an* and *bn* with a numerical suffix and rotary off normal contacts *anr1* and *bnr1*. Each vertical and rotary magnet has an armature operated contact designated *av*, *bv* and *ar*, *br* respectively while *as* and *bs* are contacts which are closed when the wipers of switches A and B are stepped respectively to the 11th contacts in a level. Two switching relays HA and HB are provided, one for each switch, the relay operated being that corresponding to the switch used as a group selector in a connection.

Each switch has 6 wipers and corresponding banks. Wipers AF1—AF3 engage banks connected to one group of 100 subscribers' lines and wipers BF1—BF3 engage banks connected to another group of 100 subscribers' lines, while wipers AS1—AS3 and BS1—BS3 engage banks connected to 2 groups of 100 outlets each. The incoming subscribers' lines of one group which will for convenience be termed group A are connected to switch A while the incoming lines of the other group, group B, are connected to switch B.

The lines of a group are connected in levels of 10 contacts each in the usual manner and a common starting wire from the line circuit is provided for each level of lines. These starting wires are connected to the level marking contacts in the banks of the respective switches, the contacts being multiplied over a number of switches, 100 and also over suitable resistances to a start relay A in a control circuit, there being a start relay A for each group of lines, the start relays being in different control circuits.

A control circuit is shown in Figs. 2a and 2b and it will be seen that the start wires SWA associated with group A of incoming lines are normally connected to relay A but should the control circuit shown be in use when a call is made the start circuit is extended to a start relay B in the

alternative control circuit, viz. that normally associated with group B of incoming lines. Similarly a call originating in group B normally causes the operation of the start relay A in the alternative control circuit shown in Fig. 2a, but if this circuit is busy the start circuit is directed to relay B of the control circuit shown fully. The two control circuits are similar and the operations concerned with the circuit shown only will be described.

Associated with the control circuit for the purpose of connecting it to a free link circuit are two single motion switches denoted by the wipers PA1—PA8 and PB1—PB8, the switch magnets PA1—PA8 and PB1—PB8, the switch magnets being denoted respectively by PADM and PBDM; of these switches, the bank contacts of wipers PA2—PA8 and PB2—PB8 are multiplied over the switches of the two control circuits while the bank contacts of wipers PA1 and PB1 are not so multiplied. Besides the relays mentioned the following are the principal relays: AS and BS are discriminating relays for determining which switch is to be used as a call finder and which as a group selector, RD is used to determine when the level in which a line is calling has been reached by the call finder, H is the line test relay for the calling line, AC the impulse relay, CC a dialling relay, HC the test relay for the group selector, G an interacting relay for effecting stepping of both switches and PX a relay controlling the aligning of switch PB with switch PA. Switches PA and PB are normally resting with their wipers on contacts connected to a free link circuit and when they are stepped on to such a circuit the switches A and B of that link circuit which after use are left in the positions in which they were last used are restored to their normal positions. For the purpose of description of the operation of the circuits shown this will be taken as a starting point and relay PX will be operated and held over its winding (I) and contacts px1 and sp4. In this condition the circuit of relay BT is open at contact px2 and a point in a circuit for relay T is closed at contact px3.

It will now be assumed that the control circuit is free and in the above condition and a call is originated in group A. Earth is connected to the start wire SWA corresponding to the level in which the calling line is situated consequent on the operation of the line relay and the appropriate contact in the bank ANP is marked. The earth on the start wire also operates relay A over the resistance in the starting wire circuit, contact b4 of relay B in the alternative control circuit, contact h6 of the control circuit shown and windings (I) and (II) of relay A to battery. Relay A locks up over its winding (II) contacts a1 and bc2 and opens contact a4 to prevent operation of relay B in the alternative control circuit, when the calling line is found. Contact a2 prepares for engaging the link circuit, contact a3 prepares a circuit for discriminating relay AS and contact a5 closes a circuit for relay T. Relay T operates and at contact t1 connects earth for the operation and holding of many of the relays and completes the circuit of relay AS which operates and locks up over its contact as1 independently of relay A. Contacts t2 and t3 disconnect relay SP and in conjunction with contacts a2 and as2 connect earth to the test wires of the link circuit to mark the latter engaged. Contact t4 connects winding (I) of relay G to wiper PA2, contact t6 connects winding (II) of relay G over contacts rd2 and bs6 to wiper PB8 and contact t5 closes a point in the circuit of vertical magnet

BV of switch B which in the case of a call originating in the group A of incoming lines will serve as a group selector. The operation of relay AS closes at contact as5 a circuit for vertical magnet AV of switch A which will act as a call finder and at contact as4 prepares a circuit for the rotary magnet AR of the same switch. Contact as3 closes a point in a circuit over the left hand winding of relay AC, wiper PB3 and wiper AF1 of switch A and contact as6 disconnects relay B to prevent interference should a call be extended thereto consequent on the alternative control circuit being engaged in which case the overflow meter OM would be operated. Vertical magnet AV now operates in the following circuit, earth over contacts g1, rd3, as5, wiper PA5, rotary off normal contact anr1 of switch A, magnet AV to battery. The magnet attracts its armature and closes contact av thereby operating relay G over wiper PA2 and winding (I) of the relay. Contact g1 opens releasing the magnet which thereupon opens its contact av releasing relay G. Contact g1 recloses and again completes the magnet circuit. This interaction between the vertical magnet and relay G continues until switch A is stepped to the level in which the calling line is connected. When the switch takes its first step the vertical off normal contacts are operated, contact an1 connecting the release magnet AZ to the contact in the bank of wiper PA3 and contacts an2 connecting the test wiper BS3 to contact br operated by the armature of rotary magnet BR for the purpose of effecting rotation of switch B as a group selector over busy outlets. Contact an3 performs no useful function in this connection but should the call have reached the link from group B it would have closed a point in the testing circuit over wiper AS3, switch A in that event, being used as the group selector.

When switch A reaches the level containing the calling line a circuit is closed from earth on the level marking contact ANP over the vertical wiper co-acting therewith, contact bn3, wiper PB8, contacts bs6, t6, rd2 winding (II) of relay G to battery. Relay G therefore remains held over this circuit after the vertical magnet releases and at contact g2 allows relay RD, which is too slow in operation to operate during the stepping of the vertical magnet, to operate. Relay RD locks up over contacts rd1 and t1 and disconnects winding (II) of relay G at contact rd2 connecting winding (I) of relay HC to wiper PB8. Contact rd3 opens the call finder vertical magnet circuit and prepares the rotary magnet circuit, contact rd4 closes but contact g3 is not closed long enough to effect release of relay A which is short circuited by it.

Consequent on the change over of contact rd2 relay G releases and at contact g1 completes the following circuit: earth over contacts g1, rd3, h5, as4, wiper PA4 rotary magnet AR to battery. The magnet operates and closes its contact ar thereby operating relay G in a circuit over its winding (I) and wiper PA2 and relay G and magnet AR interact with one another to effect rotation of the wipers of switch A. At the first rotary step rotary off normal contact anr1 is operated to disconnect magnet AV and prepare a circuit for relay HE. The calling line is marked in the test bank of the call finder by battery potential over the winding of the cut off relay and when the wipers reach the contact connected to this line a circuit is closed from this battery connection over wipers AF3, PA7, contact t2, b2, as2, left hand winding of relay H

to earth. Relay H operates and locks up over contacts h_1 and t_1 and opens the magnet circuit at contact h_5 .

Contact h_2 connects direct earth to operate the line cut off relay and contacts h_3 and h_4 connect the incoming speaking wires over contacts h_3 , h_4 , wipers PB3, PB5, contacts as_3 , and bs_3 , h_3 and h_4 , cc_4 and t_2 in parallel to earth and battery over both windings of relay AC. When the calling line is switched through by the cut-off relay, relay AC operates over the calling loop.

Contact ac_1 closes circuits for relays BC and CC. Relay BC operating disconnects earth from the locking circuit of relays A and B, releasing the operated relay at contacts bc_2 and closes a holding circuit for relay T at contact bc_1 independently of relay A. Relay CC operating, contact cc_1 prepares the impulsing circuit to the vertical magnet of the group selector, and contact cc_2 opens a point in a circuit for the rotary magnets AR and BR. Contact cc_3 prepares a circuit for relay TY of a timing device for the forced release of the control circuit should no impulse be received within a predetermined time and contact cc_4 opens to render contact t_2 of relay TZ in the timing device effective. The common start wire is extended by contact h_6 over contact a_4 to the alternative control circuit, earth being disconnected from the start wire if no other line is calling by the operation of the line cut-off relay.

The caller now receives dialling tone over wire DTL and contacts bt_3 , h_3 , as_3 and wiper PB3 and commences to dial the wanted number. The impulses for setting the group selector of the link circuit are received by relay AC and are repeated at contact ac_1 in a circuit over contacts cc_1 , bs_5 , t_5 , wiper PA6, contact bn_1 to vertical magnet BV of switch B. Relay CD operates in a parallel circuit and locks up over its make-before-break contact cd_1 and contact t_1 and at contact cd_2 makes relay CC dependent for continued energization on the back of contact ac_1 . Contact cd_3 closes a point in a circuit for the group selector rotary magnet, contact cd_4 prepares a circuit for relay BT which circuit is closed effectively if no free outlet is encountered by the group selector and contact cd_5 opens in the circuit of winding (II) of relay BT. On the first vertical step of switch B the vertical off normal contacts are operated, contact bn_1 connecting the release magnet EZ to the contact in the bank of wiper PA3, contact bn_3 disconnecting the contact in the bank of wiper PB8 from the vertical marking bank ANP and connecting it to the test wiper BS3. Contact bn_2 is without effect in this connection but in a connection in which switch B is used as a call finder it connects the test wiper AS3 to contact ar for the automatic stepping of switch A in search of a free outlet.

At the end of the impulse train relay AC remains steadily operated and relay CC releases closing the following circuit, earth over contacts g_1 , rd_3 , h_5 , cc_2 , cd_3 , hc_2 , bs_4 , wiper PB2, rotary magnet BR to battery. The rotary magnet operates, steps the wipers of switch B into the bank and closes its contact br thereby connecting the test wiper BS3 over contact an_2 and wiper PA2 to relay G. If the first outlet is busy the test bank contact will be at earth potential and relay G will operate and open the magnet circuit. The magnet releases and opens the circuit of relay G which releases and re-closes the magnet circuit, magnet BR and relay G interacting with one another to step the wipers around the level so long

as busy outlets are encountered. If no free outlet is encountered the wipers are stepped on to the last contacts in the level whereupon shaft contacts bs are closed maintaining relay G energized and thereby bringing the switch to rest. A circuit is now held closed for relay BT over its winding (I), contacts cd_4 , sp_1 and g_3 and relay BT which is slugged at its armature and is energized for sufficient time to permit it to operate.

Contact bt_1 closes but is without effect as contact cd_5 is open and contact bt_3 connects the busy tone over wire BTL and wiper PB3 to the calling line and the caller hearing the tone replaces his receiver and clears the connection. If, however, the wipers of switch B as a group selector find a free outlet battery potential will be found on the test bank contact. Relay G will not operate but relay HC will in a circuit from earth over its winding (I), contact rd_2 , t_6 , bs_6 , wiper PB8, contact bn_3 and wiper BS3. Relay HC locks up over its winding (II), contacts hc_1 , rd_1 and t_1 and opens the rotary magnet circuit at contact hc_2 , connects earth over contacts hc_3 , as_5 , wiper PA5 and contact an_1 to switching relay HB and at contact hc_4 opens a point in the connection of relay G to armature contact $padm$ of magnet PADM. Relay HB operates and connects itself to the test wire at contact hb_1 , the relay holding over the test wiper BS3 to earth connected to the test wire in the succeeding circuit after the connection has been switched through at contacts hb_2 , hb_3 and hb_4 . The link circuit remains in this condition during the conversation and on its conclusion relay HB releases and the switches A and B remain with their wipers on the contacts on which they were last used until the circuit is again picked up by switch PA. Relay AC is now disconnected and releases, contact ac_1 falling back opening the circuit of relay BC which releases after a short interval. Contact bc_2 re-

connects the holding earth for relays A and B, contact bc_1 releases relay T which in turn releases relays HC, CD and RD. On the release of relay T a circuit is closed over back contact t_1 , contacts bc_3 and rd_5 for the right hand winding of relay SP which operates and on the release of relay HC closes a circuit from earth over contacts $padm$, sp_2 and hc_4 for winding (I) of relay G. Contact sp_4 releases relay PX, contact sp_3 opens to guard relay BT (winding (I)) against closure of contact px_2 , a possible circuit for this winding being opened at contact cd_4 and contact sp_1 , closes in a circuit for magnet PADM which is closed by the operation of relay G. The magnet operates and steps the switch PA and when relay RD releases relay SP is left dependent for continued operation on earth from busy link circuits connected over the test wires and wipers PA7 and PA8. Operation of magnet PADM opens the circuit of relay G and the magnet and relay G interact with one another to step the wipers of switch PA in search of a free link circuit. When such a circuit is encountered relay SP releases, releases relay G at contact sp_2 and at contact sp_3 closes a circuit for winding (I) of relay BT. Relay BT operates, connects earth over contacts bt_2 and $padm$ to magnet PBDM and at contact bt_1 connects earth over low resistance winding (II) of relay BT, contact cd_5 , wiper PA3, contacts an_1 and bn_1 to release magnets AZ and BZ of the link circuit found. The magnets operate and release the switches of the link circuit.

The bank contacts of wipers PA1 and PB1 are connected together, the contacts in the bank of wiper PB1 being connected to contacts one ahead

in the direction of rotation of the wipers in the bank of wiper PA1. Switch PA having been stepped from the position in which it was last used and switch PB not having been stepped 5 there is no circuit over wipers PA1 and PB1 for winding (II) of relay PX consequently on the closure of contact b_{t2} magnet PBDM operates and the switch self steps until wiper PB1 rests on contacts connected to those on which wiper PA1 is 10 resting whereupon relay PX operates over its winding (II) and holds magnet PBDM operated and consequently contact $pbdm$ open and locks up over its winding (I), contacts $px1$ and $sp4$ and releases relay BT at contact $px2$. Relay BT 15 releasing allows magnet PBDM to release and advance its wipers one step whereby switches PA and PB are brought into alignment and rest with their wipers on contacts connected to the same link circuit. Relay PX remains operated over its 20 high resistance winding (I) and all the other relays in the control circuit are in their un-energized condition.

When the calling line was found by the call 25 finder and was switched through to the link circuit relays AC and CC were operated and contact $cc3$ closed a point in the circuit of relay TY. Relays TY and TZ are part of a timing device and a continuously rotating cam applies earth periodically to wire Y and after the elapse of a 30 predetermined interval after every such application applies earth momentarily to wire Z. The first application of earth to wire Y after the operation of relay CC operates relay TY which locks up over its make-before-break contact $ty1$ 35 and connects relay TZ to wire Z at contact $ty2$. If a train of impulses has not been received by the time earth is applied to wire Z relay TZ operates and locks up over its make-before-break contact $tz1$ and at contact $tz2$ opens the loop for relay 40 AC, contact $cc4$, being open, and this relay releases and contact $tz3$ opens to release relay CC, relay CD operating due to the release of relay AC. Consequent on this operation an impulse is transmitted to the vertical magnet of the group selector 45 in the link circuit, which is stepped to the first level. This level may have no outlets connected to it and the test bank contacts with the exception of the last contacts may be earthed so that the wipers are rotated to the last contacts 50 in the level where the shaft contacts are operated and relay G held energized. Relay BT then operates as previously described and busy tone is connected to the calling line.

Should the calling subscriber clear before the 55 call finder has found the line and should there be no other line in the group calling the earth on the level marking bank will be disconnected and if the level has not yet been reached the call finder will continue to step until the last level is 60 reached. The marking contact corresponding to this level is permanently earthed so as to stop the switch in this level. Relay G then operates and operates relay RD. Then and also in the case where the subscriber clears during rotary search 65 the wipers are rotated to the last contacts where relay G is held over shaft contacts. A short circuit is now closed over contacts $g3$, $sp1$, $cd4$, $rd4$ for the start relay operated and this releases, releasing relay T and the discriminating relay and 70 relay RD. During the release period of relay RD relay SP operates to initiate stepping of switch PA to a further free link circuit in the manner described.

If when the call was initiated the control circuit 75 shown was already engaged and the call finder

had found the calling line relay H would be operated and the earth on the start wire SWA would be extended over contact $b4$ of start relay B in the alternative control circuit, supposing this to be free, contacts $h6$, $a4$ of the control circuit shown, contact $as6$ of relay AS in the alternative control circuit to relay B therein and the call would have been set up under the control of the alternative control circuit.

If, however, a call is initiated in the group B of incoming lines and the alternative control circuit is in use so that either relay A or relay H therein is already operated the earth on start wires SWB will be extended after the operation of relay H and release of relay A over contacts $b4$ of relay B in the control circuit shown, contacts $h6$ and $a4$ in the alternative control circuit, contact $as6$ to relay B. Relay B operates and locks up and operates relay T by closing contacts $b5$. After the operation of relay T relay BS operates over contact $b3$ and locks up over contact $bs1$. Relay BS performs similar functions to relay AS and its operation determines that switch B which has access to incoming lines in group B over its wipers BF1—BF3 is used as a call finder and switch A 100 which has outlets to a subsequent circuit connected to the banks associated with wipers AS1—AS3 is used as a group selector. The earth on the start wire SWB marks the level in the group of marking contacts BNP corresponding to 105 that in which the calling line is situated. Relay BS at contact $bs2$ closes the circuit for operating magnet BV to step switch B in search of the marked level. Magnet BV and relay G interacting by means of contacts $g1$ and bv connected in 110 the relevant circuits. The earth on the contact of the set BNP is extended when the switch B reaches the marked level over wiper PB7 and contact $bs6$ to hold relay G and relay RD operates. Contact $bn2$ connects the test wiper AS3 115 to contact ar for stepping switch A over busy outlets. The rotary magnet is then operated to rotate the wipers over the level in search of the calling line, the magnet circuit being from earth over contacts $g1$, $rd3$, $h5$ back of contact $as4$ and 120 wiper PB2. Contacts br and $g1$ effect interaction to step the switch. Relay H operates when the line is found and when the latter has been switched through contact $as3$ being unoperated and contact $bs3$ operated relay AC is operated 125 over wipers PB4 and PB6, contacts $ha3$ and $ha4$, wipers BF1 and BF2 and the calling loop. Impulses for stepping the group selector are repeated 130 by relay AC over contacts $ac1$, $cc1$, $bs5$ front; wiper PA5 to magnet AV and at the end of the train 135 relay CC releases and rotary magnet AR is stepped by interaction with relay G, the magnet circuit being over contacts $g1$, $rd3$, $h5$, $cc2$, $cd3$, $hc2$, $bs4$ front and wiper PA4. Relay HC operates over contacts $rd2$, $t6$, $bs6$ and wiper PB7, contacts $an3$ 140 and wiper AS3 to battery on the test bank contact of a free link and operates relay HA over contacts $bnr1$, wiper PA6, contacts $t5$, $bs2$ and $hc3$ and the connection is switched through over contacts $h22$, $ha3$ and $ha4$.

Consequent on the operation of start relay B, contact $b4$ connects the start wire SWB directly to relay B so that should the alternative control circuit become free before the later calling line is found release of relay H in the alternative control circuit will not bring about operation of relay A therein until the later calling line has been found whereupon, relay B being released earth continuing on the start wire due to initiation of a further call will operate relay A and the alter- 145

native control circuit will be taken into use for the control of the switches of another link circuit.

What I claim as new and desire to secure by Letters Patent is:

1. In a telephone system, a link circuit comprising two selecting switches, groups of lines accessible to the first of said switches, different groups of lines accessible to the second of said switches, means for operating the first switch as a finder to find a line in one of said first groups of lines and for thereafter operating the second switch as a group selector to select an idle line in one of said different groups of lines to extend a telephone connection, and means for operating the second switch as a finder to find a line in another of said different groups of lines and for thereafter operating the first switch as a group selector to select an idle line in another of said first groups of lines to extend another telephone connection. 80
2. In a telephone system, two groups of lines, each group of lines being associated with a different switching stage in establishing telephone connections, a selecting switch having access to both groups of lines, means for seizing said switch for establishing a telephone connection, and means for operating said switch in a backward hunting movement over one of said groups of lines or for operating said switch in a forward selecting movement over the other of said groups of lines dependent upon the switching stage said seized switch is to be used in. 85
3. In a telephone system, subscribers' lines, trunk lines, a switch having access to said subscribers' lines and said trunk lines, means for seizing said switch for establishing a telephone connection, and means for operating said switch as a finder to find a calling subscriber's line or for operating said switch as a selector to select an idle one of said trunk lines dependent upon whether a subscriber's line is initiating a call at the time of the switch seizure or is thereafter further extending a telephone connection after the switch seizure. 90
4. In a telephone system, subscribers' lines, trunk lines, a switch having access to said subscribers' lines and said trunk lines, and means for operating said switch in a backward hunting movement to connect with a calling subscriber's line in response to a call on said line or for operating said switch in a forward selecting movement to connect with an idle one of said trunk lines in case said switch is connected to a subscriber's line by another switch. 95
5. In a telephone system, subscribers' lines, trunk lines, a first and a second switch, wipers in said switches having access to said subscribers' lines and said trunk lines, a link circuit connecting the wipers of the first switch to the wipers of the second switch, means for operating the wipers of either one of said switches in a backward hunting movement to connect said link circuit to a calling subscriber's line in response to a call on said line, and means for then operating the wipers of the remaining one of said switches in a forward selecting movement to select an idle one of said trunk lines and connect said link circuit thereto. 100
6. In a telephone system, trunk lines, a group of subscribers' lines divided into two sub-groups, a first and a second switch, wipers in said first switch having access to said trunk lines and to the first sub-group of subscribers' lines, wipers in said second switch having access to said trunk lines and to the second sub-group of subscribers' lines, a link circuit connecting the wipers of said first switch to the wipers of said second switch, means for operating the wipers of the first switch in response to a call by a calling subscriber in the first sub-group or the wipers of the second switch in response to a call by a calling subscriber in the second sub-group in a backward hunting movement to connect said link circuit to the calling line, and means for then operating the wipers of the remaining one of said switches in a forward selecting movement to select an idle one of said trunk lines and connect said link circuit thereto. 105
7. In a telephone system, subscribers' lines, trunk lines, a first and a second switch, a first set of wipers in each switch having access to said subscribers' lines, a second set of wipers in each switch having access to said trunk lines, a link circuit connecting the first set of wipers in said first switch to the second set of wipers in the second switch and connecting the second set of wipers in the first switch to the first set of wipers in the second switch, means for operating the wipers of either one of said switches in a backward hunting movement to connect the first set of wipers to a calling subscriber's line in response to a call on such line, and means for thereafter operating the wipers of the remaining switch in a forward selecting movement to select an idle one of said trunk lines over the second set of wipers and connect said link circuit thereto. 110
8. In a telephone system, subscribers' lines, trunk lines, a switch, a first set of wipers in said switch having access to said subscriber's lines, a second set of wipers in said switch having access to said trunk lines, and means for operating said switch as a finder to connect said first set of wipers with a calling subscriber's line or as a selector to connect said second set of wipers with an idle one of said trunk lines dependent upon whether a subscriber's line is initiating a call or is further extending a call after being connected to said switch by another switch. 115
9. In a telephone system, subscribers' lines, trunk lines, a first and a second switch, wipers in said switches having access to said subscribers' lines and said trunk lines, a link circuit connecting the wipers of the first switch to the wipers of the second switch, means responsive to the initiation of a call on one of said subscriber's lines for initiating the operation of the wipers of either one of said switches in a backward hunting movement, means for automatically continuing the hunting movement, means responsive to the wipers of the operated switch finding the calling line for stopping said hunting movement with the said wipers in engagement with the calling line, means for thereafter transmitting impulses over said calling line and the wipers in engagement therewith, and means for operating the wipers of the remaining one of said switches in a forward selecting movement in response to said transmitted impulses to select an idle one of said trunk lines and connect said link circuit thereto. 120
10. In a telephone system, trunk lines, a group of subscribers' lines divided into sub-groups, a plurality of link circuits, a first and a second switch in each link circuit, each first switch having access to one of said sub-groups of lines and to said trunk lines, each second switch having access to another of said sub-groups of lines and to said trunk lines, control apparatus common to said plurality of link circuits, a different path 125
11. In a telephone system, subscribers' lines, trunk lines, a first and a second switch, a first set of wipers in each switch having access to said subscribers' lines, a second set of wipers in each switch having access to said trunk lines, a link circuit connecting the first set of wipers in said first switch to the second set of wipers in the second switch and connecting the second set of wipers in the first switch to the first set of wipers in the second switch, means for operating the wipers of either one of said switches in a backward hunting movement to connect the first set of wipers to a calling subscriber's line in response to a call on such line, and means for thereafter operating the wipers of the remaining switch in a forward selecting movement to select an idle one of said trunk lines over the second set of wipers and connect said link circuit thereto. 130
12. In a telephone system, subscribers' lines, trunk lines, a first and a second switch, a first set of wipers in each switch having access to said subscribers' lines, a second set of wipers in each switch having access to said trunk lines, a link circuit connecting the first set of wipers in said first switch to the second set of wipers in the second switch and connecting the second set of wipers in the first switch to the first set of wipers in the second switch, means for operating the wipers of either one of said switches in a backward hunting movement to connect the first set of wipers to a calling subscriber's line in response to a call on such line, and means for thereafter operating the wipers of the remaining switch in a forward selecting movement to select an idle one of said trunk lines over the second set of wipers and connect said link circuit thereto. 135
13. In a telephone system, subscribers' lines, trunk lines, a first and a second switch, a first set of wipers in each switch having access to said subscribers' lines, a second set of wipers in each switch having access to said trunk lines, a link circuit connecting the first set of wipers in said first switch to the second set of wipers in the second switch and connecting the second set of wipers in the first switch to the first set of wipers in the second switch, means for operating the wipers of either one of said switches in a backward hunting movement to connect the first set of wipers to a calling subscriber's line in response to a call on such line, and means for thereafter operating the wipers of the remaining switch in a forward selecting movement to select an idle one of said trunk lines over the second set of wipers and connect said link circuit thereto. 140
14. In a telephone system, subscribers' lines, trunk lines, a first and a second switch, a first set of wipers in each switch having access to said subscribers' lines, a second set of wipers in each switch having access to said trunk lines, a link circuit connecting the first set of wipers in said first switch to the second set of wipers in the second switch and connecting the second set of wipers in the first switch to the first set of wipers in the second switch, means for operating the wipers of either one of said switches in a backward hunting movement to connect the first set of wipers to a calling subscriber's line in response to a call on such line, and means for thereafter operating the wipers of the remaining switch in a forward selecting movement to select an idle one of said trunk lines over the second set of wipers and connect said link circuit thereto. 145
15. In a telephone system, subscribers' lines, trunk lines, a first and a second switch, a first set of wipers in each switch having access to said subscribers' lines, a second set of wipers in each switch having access to said trunk lines, a link circuit connecting the first set of wipers in said first switch to the second set of wipers in the second switch and connecting the second set of wipers in the first switch to the first set of wipers in the second switch, means for operating the wipers of either one of said switches in a backward hunting movement to connect the first set of wipers to a calling subscriber's line in response to a call on such line, and means for thereafter operating the wipers of the remaining switch in a forward selecting movement to select an idle one of said trunk lines over the second set of wipers and connect said link circuit thereto. 150

- for each sub-group of lines connecting such lines to said common apparatus, means responsive to a call on one of said subscribers' lines for seizing said common apparatus over the path associated with the sub-group containing the calling line, and means dependent upon the path over which said common apparatus is seized for operating either the first or the second switch in an idle one of said link circuits as a finder to find the calling line and then the remaining switch in said link circuit as a selector to select an idle trunk line.
11. In a telephone system, subscribers' lines, trunk lines, a first and a second switch each having wipers, a link circuit, two switching relays in said link circuit, means for operating the wipers of either one of said switches in a primary and a secondary movement to connect said link circuit to a calling subscriber's line in response to a call on said line, means for thereafter operating the wipers of the remaining one of said switches in a primary and secondary movement to connect said link circuit to an idle one of said trunk lines, and means for operating only the first of said switching relays in case the wipers of said first switch are connected to said calling line or for operating only the second of said switching relays in case the wipers of the second switch are connected to said calling line to extend the connection from the calling line to said trunk line.
12. In a telephone system, trunk lines, a group of subscribers' lines divided into sub-groups, a plurality of link circuits, a first and a second switch in each link circuit, each first switch having access to one of said sub-groups of lines and said trunk lines, each second switch having access to another of said sub-groups of lines and to said trunk lines, control apparatus common to said plurality of link circuits, a hunting switch associated with said common apparatus, means for operating said hunting switch to maintain said common apparatus in connection with an idle one of said link circuits, a start circuit for each sub-group of lines connected to said common apparatus, means responsive to a call on one of said subscribers' lines for seizing said common apparatus over the start circuit associated with the sub-group containing the calling line, and means dependent upon the start circuit over which said common apparatus is seized for operating either the first or the second of said switches in said selected idle link circuit as a finder to find the calling line and then the remaining switch in said link circuit as a selector to select an idle trunk line.
13. In a telephone system, a group of subscribers' lines divided into a first and a second sub-
- group, trunk lines, a first and a second link circuit, a first and a second switch in each link circuit, the first switch in the first link circuit and the second switch in the second link circuit having access to said first sub-groups of lines and said trunk lines, the second switch in the first link circuit and the first switch in the second link circuit having access to the second sub-group of lines and said trunk lines, a first and a second control apparatus for said link circuits, a first and a second start relay in each control apparatus, a start circuit for each sub-group of lines, said start circuits normally connected to the first start relays in said apparatuses, means responsive to a call on one of said subscribers' lines for operating the first start relay in one of said control apparatuses if idle or if said one control apparatus is busy for operating the second start relay in the other of said control apparatuses over the start circuit associated with the sub-group containing the said calling line, and means for operating the first switch as a finder to find the calling line and the second switch as a selector to select an idle trunk in one of said link circuits in case the first start relay in one of the apparatuses is operated or for operating the second switch as a finder to find the calling line and the first switch as a selector to select an idle trunk line in the other link circuit in case the second start relay in the other apparatus is operated.
14. In a telephone system, trunk lines, a group of subscribers' lines divided into sub-groups, a plurality of link circuits, a first and a second switch in each link circuit, each link circuit comprising only the operating magnets of said switches and only two switching relays, control apparatus common to said plurality of link circuits, means for operating said common apparatus to select an idle link circuit, means responsive to a call on one of said subscribers' lines for seizing said common apparatus, means in said common apparatus responsive to its seizure for operating the operating magnets of either the first switch or the second switch of the selected link circuit dependent upon the sub-group the calling line is in to operate said switch as a finder to find the calling line, means in said common apparatus for thereafter operating the operating magnets of the remaining switch in said selected link circuit as a selector to select an idle one of said trunk lines, and means in said common apparatus for thereafter operating only one of said switching relays, the relay operated being dependent upon the functions performed by the respective switches in the said link circuit.

REGINALD GRIFFITH DIXON,
